MACHINE FOR PACKING BUNS AND THE
LIKE IN CARTONS

Clement F. Johnsen, Santa Monica, Calif., and
Clement C. Johnsen, Phoenix, Ariz.; said
Clement F. Johnsen assignor to Roy C. Johnsen,
Phoenix, Ariz.

Application December 18, 1947, Serial No. 792,568

30 Claims. (Cl. 53—41)

1

The present invention relates generally, as indicated, to a machine for packing buns and the like into cartons, and more especially to certain improvements in a machine of the general type disclosed in Patent No. 2,307,510, which issued to one of us, viz. Clement C. Johnsen, on January 5, 1943.

One of the primary objects of this invention is to provide a machine which is capable of packaging and slicing, if desired, buns and like baked goods without handling thereof by the operator between the oven and shipping.

Another object of this invention is to provide a machine having an improved form of feeding device whereby the buns or the like may be transported from a feeding zone to a collecting zone without smashing or otherwise damaging the same.

Another object of this invention is to provide a machine in which the operation of the carton feeding and unfolding device is conditioned upon there being a supply of buns or the like carried by the machine from the collecting zone to a packaging zone.

Other objects and advantages will become apparent as the following description proceeds.

To the accomplishment of the foregoing and related ends, said invention, then, comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In said annexed drawings:

Figs. 1 and 1a are top plan views of contiguous portions of a preferred embodiment of our invention;

Figs. 2 and 2a are side elevation views of contiguous portions of the machine illustrated in Figs. 1 and 1a respectively, with the carton supply container removed from the lefthand end of the machine as viewed in Fig. 2;

Fig. 3 is a side elevation view of the carton supply container;

Figs. 4 and 5 are transverse cross section views of the machine taken substantially along lines 4—4 and 5—5, of Figs. 1a and 1, respectively;

Fig. 6 is an enlarged fragmentary view of a portion of the righthand end of the machine as viewed in Fig. 2a;

Figs. 7 and 8 are elevation views of a portion of the lefthand end of the machine as viewed in Fig. 2 illustrating two positions of such portion of the machine;

Fig. 9 is a fragmentary elevation view partly in section of another portion of the machine at the lefthand end thereof as viewed in Fig. 2;

Fig. 10 is a fragmentary elevation view of the

lower portion of the machine to which the mechanism of Figs. 7 and 8 is connected;

Fig. 11 is an enlarged fragmentary view in side elevation of that portion of the bun carrying mechanism disposed in zone D of Fig. 2;

Fig. 12 is a fragmentary plan view of the mechanism shown in Fig. 11; and

Fig. 13 is a view in perspective of a carton adapted to be unfolded by mechanism of zone E of Fig. 2.

Referring now to the drawings and first more especially to Figs. 1 and 1a, and 2 and 2a, the machine as a whole comprises a longitudinally extending base 1 divided into a plurality of zones, viz. A through E, starting from the righthand end of the base which respectively comprise feeding, collecting, transferring, slicing, and packaging zones. The buns or the like deposited into the feeding zone A are carried thereby to and collected in the collecting zone B wherefrom they are carried in the zone C to the packaging zone E subjected, if desired, during such carriage in zone C to splitting or slicing in the zone D.

As best shown in Fig. 2a, the righthand end 25 of base 1 has a frame 2 projecting longitudinally therefrom, said frame having formed in its upper surface a plurality of longitudinally extending channels or grooves 3 (see Figs. 1a and 4) which converge toward the collecting zone B. Mounted 30 on frame 2, spaced slightly above the channels 3, are a plurality of vertically disposed partition strips 4. The opposite ends of the partition strips 4 are respectively fixedly mounted to the frame 2 as by cross braces 5, 6, and 7, 8, 9, the left- 35 hand ends, as viewed in Fig. 1, being closer together than the righthand ends whereby to define spaces which converge in substantially the same manner as the channels 3. It is further to be noted that the channels 3 are narrower than the spaces between strips 4 and are disposed to one side or offset transversely as best shown in Fig. 4 whereby to provide edges which cause tipping or tilting of the buns when dumped between strips 4. At the opposite sides of the base, 40 longitudinally extending members provide similar edges about which the buns tip or tilt.

Rotatably supported at the ends of frame 2 below the channeled upper surface thereof are two pairs of parallel sprocket wheels 10 and 13 over each pair of which is trained a chain 11. On each chain are a series of longitudinally spaced brackets 12 in which exciter bars 14 are rotatably supported, said bars extending transversely across the frame above the channels 3 and below the 45 lower edges of the strips 4. Said bars are movable longitudinally of the frame 2 from right to left, as viewed in Figs. 1a and 2a, in response to rotation of the sprocket wheels 10 and 13 in a counter-clockwise direction. Each of said bars is of non-circular cross section, preferably of hexagonal or

other polygonal shape. In order to rotate said bars during movement thereof between the channels 3 and strips 4 one end of each bar has a gear 15 fixed thereto, which gear is engageable with a longitudinally extending rack 16 secured to frame 2. To assure proper meshing of said gears with said rack, the frame has mounted thereon, as shown in Fig. 6, a spring member 17 which is operative to properly rotate each gear 15 just prior to the engagement thereof with the rack 16, said spring member 17 being in the form of a finger adapted to engage each gear 15 forward of the center and as each said gear 15 approaches the rack 16 to allow the gear to pass underneath said finger whereupon the free end of said finger will engage between the gear teeth to cause a rotation of said gear 15 to a predetermined position irrespective of the initial rotary position of said gear at the time of initial engagement with said finger.

Rotatable with the sprocket wheels 10 and outwardly adjacent each wheel is a guard disk member 21 and a feeding disk 18, said latter disk being provided with circumferentially spaced radial projections 19 thereon, such projections 19 being synchronized with the travel of the exciter bars 14.

Although any conventional form of hopper means may be employed for furnishing buns and the like to the afore-described feeding device, it is preferred to employ a standard baking tray 20 which is adapted to be placed between the guard disks 21 and moved toward the feeding disks 18 whereupon the projections 19 on the latter will engage a flange 22 on the tray for lifting that end of the tray upward. The operator of the machine then quickly tips the tray so that its upper edge lands on the stops 23 on frame 2, the contents of the tray being thereby dumped into the space between the strips 4 and in the channels 3 assuming positions as indicated by the dot-dash lines in Fig. 4. When the buns are positioned as illustrated the rotating and longitudinally moving exciter bars 14 will engage the buns and impart a rotating and adjusting action thereto to thus avoid the possibility of the buns being smashed or otherwise damaged during movement from zone A to zone B. From the foregoing it is apparent that the channels into which the buns are adapted to be deposited from a baking tray comprise not only the channels 3 but the spaces between the partition strips 4 as well.

At the end of zone A the buns are pushed longitudinally through the collecting zone B by means of paddles 24 which are carried by transversely disposed square rods 25 having their ends connected to parallel chains 26, said chains being trained over pairs of sprocket wheels 27 and 28. In zone B the lower edges of the strips 4 have secured thereto longitudinally extending horizontally disposed strips 29 (see Fig. 5) forming between them relatively narrow channels for the paddles 24. The paddles moving in those channels which converge are slidable on the rods 25 in a direction axially of the rods as best shown in Fig. 5. The channels formed by the strips 29 are sufficiently narrow so as to prevent the buns or the like from dropping downwardly therebetween. At the left end of zone B, movement of the buns is arrested by a plurality of upwardly curved fingers 30 projecting from the cross brace 9 and disposed between the partition strips 4. At this point the paddles 24 are free to swing clear of the buns as by disengagement of the roller 36 75

on each rod carried by the end of a rearwardly extending arm 32 on rod 25 from a guide means 37 provided on frame 2. The frame has suitable guide supports 33 and 34 for the chains 26. The other end of each rod 25 likewise has a guide roller 31 rotatably mounted at the rearward end of an arm 32.

Following the collection of the buns or the like on fingers 30 they are ready for transportation through the zone C. This portion of the machine which includes a carriage device comprises two pairs of sprocket wheels 38 and 39, each of which is non-rotatably carried by shafts 40 and 41, respectively, which shafts extend transversely across the base 1. Trained over said sprocket wheels is a pair of endless chains 43 to which are attached in longitudinally spaced relation relative to the base 1 a series of cross members 44 with brackets 45 at each end. Said members 44 also have a plurality of curved arms 46 thereon adapted to engage the buns on fingers 30 and to lift them upwardly for carriage toward the left as viewed in Figs. 1 and 2. Slidably mounted in each of said members 45 is a pair of adjacent bars 47 and 48 there being a gang of plates 50 on bar 47 and another gang of plates 51 on bar 48. Said bars 47 and 48 are normally urged in a direction yieldably forcing adjacent plates 50 and 51 into clamping relation with the buns therebetween as by suitable spring means (not shown), such clamping occurring after the roller 52 on bar 47 disengages from the righthand end of the cam plate 53 fixedly mounted on base 1.

Then, if desired, the buns which are clamped between the plates 50 and 51 may be slit or sliced to any desired depth as by a gang of axially spaced rotating blades 54 which are supported above the carriage device and rotated as by a motor 55. Suitable means including a bell crank 57 are employed to adjust the depth of slicing and the transverse positions of the blades on the base relative to the buns carried by the device. This slicing operation has been previously referred to as zone D.

The brackets 45 are suitably guided in their movement by guideways 58 and 60 which receive the rollers 61 rotatably supported on the brackets.

When the buns have reached the lefthand end of base 1 the cam plate 63 is operative to engage roller 52 to thus operate the plates 50 and 51 for thereby releasing the buns so that they may drop into an unfolded carton 58, shown in dotted lines in Figs. 2 and 9. This is the packaging zone E previously referred to.

In detail, the zone E comprises a cross slide 62 mounted on base 1 having, as shown in Fig. 3, a container 64 on one side thereof into which folded cartons 58 may be stacked. A weight 65 on such stack of cartons is used to effect engagement of the lowermost carton with the upper surface of the cross slide. The stack of cartons 58 and weight 65 are not shown in Figs. 1 and 2 in order to better illustrate the parts which the cartons and weight would obscure. Slidable in the cross slide is a pusher block 66 which is provided with a pair of upstanding fingers 67 which are operative when said block is moved along the cross slide in a perpendicular direction toward the center line of base 1 to engage the lowermost carton 58 in the stack of cartons in container 64 and thus move such lowermost carton to a position where it is unfolded for receiving buns. Movement of pusher block 66 in opposite directions is effected by an arm 68 engaged therewith and pivoted to base 1 by a pin

69 connected thereto (see Fig. 10), said arm being rocked or oscillated by means of a crank shaft 71 journalled in base 1. Connected to the crank shaft 71 is a link 73 which has its lower end connected to an arm 74 which is rigid with the pin 69. It is thus apparent that when the link 73 is reciprocated by the crank shaft 71, the arm 68 is caused to oscillate fore and aft longitudinally of the cross slide 62 to thus effect the required reciprocation of pusher block 66 on the cross slide 62. The fingers 67 on the pusher block are so formed that upon return movement of the pusher block they will not engage the lowermost carton 58 but rather will be deflected so as to pass thereunder. The crank shaft 71 is driven as by sprocket wheels 75 and 76 and a chain 78 trained thereover, said sprocket wheels being respectively non-rotatably mounted on shaft 49 and crank shaft 71.

The next operation after a folded carton has been positioned under the carriage device is to unfold the carton so that it may receive buns dropped by the carriage device. The means for unfolding said cartons comprises arms 79 and 80 projecting in opposite directions from the cross slide 62, and members 81 and 82 slidable on said arms. Pivotally connected to each of said members 81 and 82 is a cam member 83 which has hooked fingers 85 thereon which are adapted to engage what constitutes the upper side edges of an unfolded carton. For unfolding the flaps 86 of a carton into an open position member 81 has a pair of fingers 87 pivotally connected thereto and urged apart in a direction longitudinally of the cross slide as by means of interengaging cam grooves 88 and pins 89. The cam members 83 are actuated by engagement of the outer ends thereof with brackets 90 provided on the arms 79 and 80.

The mechanism for reciprocating the members 81 and 82 on the arms 79 and 80 to thus effect actuation of the fingers 85 and 87 comprises a link 92 pivoted between its ends on the cross slide 62 and having links 93 and 94 respectively pivotally connected to its ends, said links 93 and 94 having their other ends pivotally connected respectively to the members 81 and 82. Rocking of the link 92 about its pivot is effected by a fork member 95 provided with a pin portion 96 engaging in a cam groove 97 in a disk 98 non-rotatably mounted on the crank shaft 71.

Also non-rotatably mounted on crank shaft 71 is another cam disk 100 which through a fork 101 and a link 102 pivoted to the base 1 at the point 103 is operative to reciprocate a rod 104. Connected to the outer end of rod 104 is a plate 105.

In order to prevent cartons from being supplied under the carriage device and unfolded thereunder when no buns are being carried by the carriage device there is provided a novel mechanism for interrupting operation of the carton feeding and unfolding device. This mechanism comprises a wedge 107 fixed on one end of bar 47, said wedge being adapted when the carriage device assumes a position such as shown in Fig. 8 without buns between the plates 53 and 54 to engage the roller 108 disposed at one end of an arm 109 pivoted to the base of the apparatus at the point 106, said arm in turn being operative to move the link 110 connected to the other end of arm 109 downwardly thereby effecting disengagement (by a crank lever 114) between a clutch collar 111 and the clutch surface 112 provided on the sprocket wheel 78. Such disengagement effects stopping of the rotation of sprocket wheel 78 through the crank shaft 71 whereby the pusher block 66 will not be reciprocated and likewise the unfolding

mechanism will not be actuated. Thus with such mechanism, cartons are fed and unfolded only when a supply of buns is being carried by the carriage device. In Fig. 7 there is shown the normally engaged position of the clutch collar 111 with wheel 76 when the wedge 107 is out of engagement with the arm 109, a spring 113 on said arm being operative to lift the link 110 upward and thus through the crank 114 and collar 111 maintain engagement of the clutch.

Driving of the apparatus is preferably effected by providing a main drive shaft 115 and sprocket wheels 116, 117, 118, and 119, respectively non-rotatably mounted on the shaft 41, and those shafts which carry the sprocket wheels 28, 27, and 13 the wheels 116 and 117 having a chain 120 trained thereover, and the wheels 118 and 119 having a chain 121 trained thereover.

In connection with the chain 78 trained over the wheels 75 and 76 there is provided an idler wheel 122 carried on a swingably adjustable arm 123 whereby the tension of said chain may be properly adjusted.

Other modes of applying the principle of the invention may be employed, change being made as regards the details described, provided the features stated in any of the following claims, or the equivalent of such, be employed.

We therefore particularly point out and distinctly claim as our invention:

1. In a machine for packing buns and the like into cartons, the combination of a longitudinally extending base, successively arranged feeding, collecting and carriage devices on said base operative to transport buns and the like placed in said feeding device at one end of said base toward the other end of said base, a carton feeding and unfolding device at such other end of said base operative to position and unfold cartons adjacent said carriage device and therebelow for receiving buns and the like dropped from said carriage device, and means for actuating all of said devices, said carriage device comprising a plurality of opposed plates adapted to yieldably clamp buns and the like therebetween, means separating said plates when the buns clamped therebetween are disposed above an unfolded carton therebelow, normally engaged clutch means between said carton feeding and unfolding device and the means for actuating the same, and clutch disengaging means associated with said carriage device operative when said plates are urged together without buns and the like therebetween to render said carton feeding and unfolding device inoperative.

2. The structure according to claim 1 further characterized in that said clutch disengaging means includes a linkage mechanism connected to a shiftable element of said clutch means, and a wedge on said carriage device engageable with such linkage only when said plates are urged together without buns therebetween, said wedge and linkage mechanism being formed with cooperating cam surfaces actuating said linkage mechanism for shifting said shiftable element in a direction effecting disengagement of said clutch means.

3. In a machine for packing buns and the like into cartons, the combination of a bun feeding device comprising a base formed with longitudinally extending channels, a series of spaced bars transversely across said base and channels, driving means engaged with said bars for moving the latter longitudinally of said base and thereby correspondingly moving buns and the like adapt-

ed to be loaded into such channels and engaged by said bars, and mutually engaged means on said base and bars imparting rotation to said bars while moving as aforesaid.

4. The structure according to claim 3 further characterized in that said mutually engaged means comprises a longitudinally extending gear rack on said base, and a gear on each of said bars in mesh with said rack.

5. The structure according to claim 3 further characterized in that the mutually engaged means includes a longitudinally extending gear rack on said base, a gear on each of said bars in mesh with said rack, and a spring finger member on said base ahead of one end of said gear rack engageable between the teeth of said gears for predeterminedly rotating the same for proper engagement with said rack.

6. The structure according to claim 3 further characterized in that a plurality of longitudinally extending partition strips are mounted on said base above such channels and spaced above said base a sufficient distance to accommodate said bars and in that such channels and the spaces between said partition strips converge in the direction of movement of said bars for positioning buns adapted to be loaded into such channels on edge and with the buns in each row closely adjacent one another.

7. In a machine for packing buns and the like into cartons, the combination of a carton feeding and unfolding device operative to predeterminedly position and to unfold cartons, a carriage device located above and adjacent to said carton feeding and unfolding device for transporting buns and depositing the same into unfolded cartons, and means for actuating said devices, said carriage device comprising a plurality of opposed plates adapted to yieldably clamp buns and the like therebetween, means separating said plates when the buns clamped therebetween are disposed above an unfolded carton therebelow, normally engaged clutch means between said carton feeding and unfolding device and the means for actuating the same, and clutch disengaging means associated with said carriage device operative when said plates are urged together without buns and the like therebetween to render said carton feeding and unloading device inoperative.

8. In a machine for packing buns and the like into cartons, the combination of a carton feeding and unfolding device operative to predeterminedly position and to unfold cartons, a carriage device located above and adjacent to said carton feeding and unfolding device for transporting buns and depositing the same into unfolded cartons, and means for actuating said devices, said carriage device comprising a plurality of opposed plates adapted to yieldably clamp buns and the like therebetween, means separating said plates when the buns clamped therebetween are disposed above an unfolded carton therebelow, a control operatively interposed between said carton feeding and unfolding device and the means for actuating the same and adapted when operated to render said last-named means inoperative to actuate said carton feeding and unfolding device, and a control operating means associated with said carriage device operative when said plates are urged together without buns and the like therebetween to operate said control and thereby render said carton feeding and unloading device inoperative.

9. In a machine for packing buns and the like

into cartons, the combination of a longitudinally extending base, successively arranged feeding, collecting and carriage devices on said base operative to transport buns and the like placed in said feeding device toward said collecting and carriage devices, a carton feeding and unfolding device operative to position and unfold cartons adjacent said carriage device and therebelow for receiving buns and the like dropped from said carriage device, and means for actuating all of said devices, said carriage device comprising a plurality of opposed plates adapted to yieldably clamp buns and the like therebetween, means separating said plates when the buns clamped therebetween are disposed above an unfolded carton therebelow, a control operatively interposed between said carton feeding and unfolding device and the means for actuating the same and adapted when operated to render said last-named means inoperative to actuate said carton feeding and unfolding device, and a control operating means associated with said carriage device operative when said plates are urged together without buns and the like therebetween to operate said control and thereby render said carton feeding and unloading device inoperative.

10. The structure according to claim 9 further characterized in that said carton feeding and unfolding device comprises a cross slide member disposed transversely across said base adjacent to and below said carriage device, a pusher block reciprocable longitudinally on said slide member, means for reciprocating said block including an arm having one of its ends engaging said block and the other of its ends connected to said base for pivotal movement about an axis disposed longitudinally of said base, a container on said slide member adapted to carry a stack of folded cartons therein with the bottom one of such cartons engaging said slide member, means on said block operative when said block is moved in one direction on said slide member to engage such bottom carton and shift the same to a position adjacent to and below said carriage device.

11. The structure according to claim 10 further characterized in that said slide member is provided with longitudinally extending arms thereon, member slidable on said arms, and hooked fingers on said members pivotally connected thereto and adapted to engage the edges of a folded carton shifted as aforesaid, said fingers and arms being provided with cooperating cam surfaces operative when said members are slid on said arms to swing said fingers about their respective pivots to lift said fingers from the edges of the carton engaged thereby after such carton has been filled with buns and the like.

12. The structure according to claim 10 further characterized in that said slide member is provided with longitudinally extending arms thereon, members slidable on said arms, fingers on said members engageable with the edges of a folded carton shifted as aforesaid and operative when said members are moved away from one another on said arms to unfold such carton, and other fingers pivotally connected on one of said members for swinging movement away from one another for engaging the closure flaps of such unfolded carton, and cooperating cam means on said other fingers and said one of said members operative when the latter is moved on its respective arm to effect swinging movement of said other fingers as aforesaid.

13. The structure according to claim 9 further characterized in that said feeding device comprises a plurality of longitudinally extending channels formed on said base into which the buns and the like are adapted to be placed, a series of spaced bars transversely across said base and channels movable longitudinally of said base toward said collecting device and engageable with the buns and the like in such channels for correspondingly moving the same, and means for moving said bars.

14. The structure according to claim 9 further characterized in that said feeding device comprises a plurality of longitudinally extending channels formed on said base into which the buns and the like are adapted to be placed, a series of spaced bars transversely across said base and channels movable longitudinally of said base toward said collecting device and engageable with the buns and the like in such channels for correspondingly moving the same, means for moving said bars, said bars being of non-circular cross-section, and mutually engaged means on said base and bars effecting rotation of said bars while they are moved longitudinally of said base and channels.

15. The structure according to claim 14 further characterized in that the mutually engaged means includes a longitudinally extending gear rack on said base, and a gear on each of said bars engageable with said rack.

16. The structure according to claim 14 further characterized in that the mutually engaged means includes a longitudinally extending gear rack on said base, a gear on each of said bars engageable with said rack, and a finger member on said base ahead of one end of said gear rack engageable with said gears for rotating the same for proper engagement with said rack.

17. The structure according to claim 9 further characterized in that means are provided on said base adjacent said feeding device for lifting an end of a tray containing buns and the like, said means including a rotating disk with circumferentially spaced radial projections thereon adapted to engage an edge of one end of a tray placed thereagainst.

18. The structure according to claim 9 further characterized in that said collecting device comprises a plurality of longitudinally extending strips defining channels converging in a direction from said feeding device to said carriage device to position buns adapted to be loaded into such channels on edge, a plurality of paddles movable longitudinally in such channels and adapted to engage successive buns and the like delivered to such channels by said feeding device for correspondingly moving the buns in rows toward said carriage device, and means slidably carrying said paddles for transverse movement relative to said base whereby said paddles may simultaneously move longitudinally and transversely of said base in such converging channels.

19. In a machine for packing buns and the like into cartons, the combination of a bun feeding device comprising a base formed with longitudinally extending channels, a series of spaced, non-circular cross-section bars transversely across said base and channels, driving means engaged with said bars for moving the latter longitudinally of said base and thereby correspondingly moving buns and the like adapted to be loaded into such channels and engaged by said bars, and mutually engaged means on said base

70
75

and bars imparting rotation to said bars while moving as aforesaid.

20. A bun feeding and collecting device adapted to receive buns in inverted position from a baking tray, to prearrange such buns on edge and into rows, and to transport such rows of buns for deposit into open cartons, comprising a longitudinally extending base formed with a plurality of longitudinally extending channels having narrower bottom portions than top portions to provide edges about which the buns are adapted to be tilted, and means movable longitudinally along said base between the bottom and top portions of such channels engaging, and thus similarly moving, the buns, such channels converging whereby to progressively further tilt the buns to positions on edge during the course of their travel longitudinally of said base.

21. The structure of claim 20 further characterized in that said means comprises a series of spaced bars transversely across said base and channels, and that mutually engaged means are provided on said base and said bars for imparting rotation to said bars while moved as aforesaid.

22. The structure of claim 20 further characterized in that the wider top portions of the channels comprise a plurality of longitudinally extending partition strips defining spaces therebetween which are offset transversely with respect to the narrower bottom portions of the channels.

23. Mechanism for opening folded cartons comprising a horizontal support for a folded carton, a horizontally disposed transverse arm on said support, a slide member reciprocable on said arm toward and away from said support, a finger unit pivotally connected between its ends to said slide member for swinging in a generally vertical plane, said finger unit having a hooked inner end adapted to engage an edge of a folded carton on said support which constitutes the top edge of one side of an unfolded carton, and cooperating cams on the outer end portions of said finger unit and said arm operative during outward movement of said slide member and finger unit to swing the latter and thus lift the side of the carton edge engaged thereby.

24. The mechanism according to claim 23 further characterized in that one of said cams comprises a roller carried on one of said finger unit and arm.

25. Mechanism for opening folded cartons comprising a horizontal support for a folded carton, a horizontally disposed transverse arm on said support, a slide member reciprocable on said arm toward and away from said support, a finger unit pivotally connected to said slide member for swinging in a generally vertical plane, said finger unit having a hooked inner end adapted to engage an edge of a folded carton on said support which constitutes the top edge of one side of an unfolded carton, cooperating cams on said finger unit and said arm operative during outward movement of said slide member and finger unit to swing the latter and thus lift the side of the carton edge engaged thereby, and driving means for positively reciprocating said slide member in opposite directions.

26. The mechanism according to claim 25 further characterized in that said driving means comprises a first link pivotally connected to said support, a second link pivotally connected at its opposite ends to said first link and to said slide member respectively, a rotatable cam disk formed

with a cam groove on one side face, and a third link including a transverse pin portion at one end engaged in such cam groove and pivotally connected at its other end to said first link whereby upon rotation of said cam disk said first link is oscillated by said third link to reciprocate said slide member through said second link.

27. The mechanism according to claim 26 further characterized in that said third link is forked at such one end, and a drive shaft is connected to said cam disk, such forked end of said third link transversely slidably straddling a portion of the cam disk and drive shaft assembly so as to be held centered with respect to the axis of said shaft while permitting radial movement of such pin portion of said third link with respect to such axis.

28. Mechanism for opening folded cartons comprising a vertically disposed open bottom container for holding a stack of folded cartons, a horizontally extending support underneath said container, a pusher block reciprocable on said support and adapted to engage an edge of the bottom carton and to displace the bottom carton to one side of said container for unfolding and means for reciprocating said pusher block, said means comprising a driving crank, a downwardly extending link pivotally connected to the crank pin of said crank, a horizontally disposed shaft rotatable in said support having a transverse arm at one end, said arm being pivotally connected at its outer end to the lower end of said link, and an upwardly extending arm keyed at its lower end to the other end of said shaft and pivotally connected at its upper end to the underside of said pusher block.

29. Mechanism for opening folded cartons comprising a horizontal support for a folded carton, means engaging the edge of a folded side of a carton to open the carton, and means unfolding a flap at the end of the carton, said last-named means comprising a transverse arm on

said support, a slide member reciprocable on said arm toward and away from said support, a finger unit pivotally connected to said arm for swinging in a generally horizontal plane, and cooperating cams on said finger unit and slide member operative to swing said finger unit in opposite directions in response to reciprocation of said slide member on said arm.

30. The mechanism according to claim 29 further characterized in that said first-named means comprises another finger unit pivotally connected to said slide member for swinging in a generally vertical plane, said another finger unit having a hooked end adapted to engage the edge of one side of a folded carton, and other cooperating cams on said arm and another finger unit operative to raise and lower the hooked end in response to reciprocation of said slide member on said arm.
